12 Claims.

(Cl. 57—130)

This invention relates principally to an improvement in adapters and securing devices for enabling the mounting of different spools or bobbins interchangeably on spinning spindles.

5 An object is to provide an adapter for said purpose which is capable of being easily and quickly mounted on and dismounted from the spindle, and which, when in working position, is locked against rotation and longitudinal movement relative to the spindle.

Another object is to provide an improved means for retaining bobbins and spools and/or adapters for bobbins and spools on spindles (e. g.) such as used in the textile industry.

15 Usually in spinning mills, the bobbins for weft yarn,—which bobbins conventionally are frustoconical paper tubes,—are mounted on the bare spindles. Since the bobbins for warp yarn are larger internally than bobbins for weft yarn, 20 interchangeable use of the two types requires an adapter of some sort for the larger if only one size of spindle is available or required to be used. Spinners frequently meet the problem by their own resources, using makeshift adapters which can be glued onto the spindle, or can be screwed 25 on, as at internal threads of the whorl, assuming appropriate threads are, or space for such threads is, available. Gluing-on is uncertain to secure concentricity between bobbin and spindle, and of course makes removal of the adapter extremely 30 difficult. Screwed-on adapters can be used only when driven in one direction, and tend to become detached from or loose on the spindle if 35 reversely driven. Any looseness can cause chattering of the spindle. Another difficulty was presented by the impracticability of leaving any 40 space or gap between the whorl and the adapter base portion into which reserve yarn could become fouled, and consequently, the adapters were 45 made with the same outer diameter at the base as the outer diameter of the neck of the whorl. Thus, each adapter was suitable for but one size 50 of bobbin tube. In another prior construction, attempt was made to secure the adapter to the whorl by means of claws, the adapter being 55 pressed tightly on the top of the spindle by means of a screw. Detachment of this adapter required special tools, and a single adapter was limited to but one size bobbin, principally because of 60 having to preserve a smooth continuous surface between the adapter and whorl as already discussed.

Practical considerations and conditions demand more flexibility of adaptation to different sized bobbins than afforded by the expedients mentioned above and heretofore known, and a satisfactory solution to the essential problem must enable rotation of the spindles in either direction, enable quick change of effective size 65 without special tools, and provide for locking of

the adapter to the spindles against rotation and endwise movement thereon. Attainment of the above indicated goal, and particularly in an adapter which can be secured to the spindle at one and preferably both ends of it by resilient 5 and/or readily releasable coupling elements is a further and more specific object hereof. Other objects and the various novel features of the exemplary constructions will become apparent from the following description relating to the accompanying drawings. The essential characteristics are summarized in the claims.

In the drawings, Fig. 1 is a longitudinal sectional view of one form of adapter, embodying the invention, in place on a spindle, the upper 15 end portions and whorl of which is shown (latter in section). Fig. 2 is a transverse section as indicated on Fig. 1; Fig. 3 is a side elevation of the whorl; Fig. 4 shows the upper portion of the spindle in longitudinal section (as at right angles to Fig. 1) and a yieldable bobbin-securing and adapter-securing member on the spindle end; Fig. 5 is a top view of the spindle; Fig. 6 is a fragmentary view partly in section showing a modified connection between the adapter and whorl; Fig. 7 is a transverse section as indicated 25 on Fig. 6; Fig. 8 is a view similar to Fig. 1 showing further modifications in upper and lower couplings for an adapter and spindle; Fig. 9 is a view similar to Fig. 6, but of a still different adapter base connection to the spindle or part 30 thereof; Figs. 10 and 11 are fragmentary side views of a spindle tip taken at right angles to each other; Fig. 12 is a view similar to Fig. 4 of a further modified spindle construction suitable 35 for use with an adapter and spindle assembly such as shown by Fig. 8, and Figs. 13 and 14 are cross-sectional views, as indicated, respectively, on Fig. 12.

Referring further to the drawings, the spindle, as adapted for use directly to support standard bobbins, is indicated at 1, and the whorl thereof at 2, attached as to a middle portion 3 of the spindle. The whorl has an upstanding rim or cup effect 4 which can be integral with the whorl proper (e. g. Figs. 8 and 9), or made 45 as a tightly fitted sleeve, e. g. Figs. 1 and 6). The rim may be used as a retaining cup for yarn at the start of the spinning operation. The adapter, in all forms, is indicated at 5, and this can be metal, organic plastics, or any other material of adequate strength. It can be drawn as 50 a tube from light gage metal.

As shown in Figs. 1 to 3, the lower end of the adapter is enlarged, as at 6, and adapted to be 55 received in the cup 4 with provision for a little play. The upper part of the adapter has a short portion peripherally fitting the adjacent spindle portion as an upper centering means for the adapter.

Coupling of the adapter detachably to the spindle may be accomplished through the medium of radially yieldable buttons 8 which are movable in lateral holes or sockets of the enlarged base 6 of the adapter. The buttons are urged outwardly by springs 9, the latter reacting inwardly on a sleeve 12. The buttons 9 have rounded nose portions for readily releasable but positive driving engagement with respectively aligned holes 14 in the rim 4 from which they protrude only slightly if at all. Such release is enabled by making the noses of the buttons and the receiving holes 14 therefor of such proportions that the buttons can easily be pressed inwardly into rim-disengaging position by the thumb and finger of an operator. The outward movement of the buttons can be limited by flanges 10 on the buttons, which outwardly abut counterbore shoulders as illustrated in Fig. 2, or an undercut boring (11, Fig. 3) extending around the inside of the adapter in the plane of the buttons and bridged by the sleeve 12 when pressed into place in the base of the adapter. The sleeve 12 is not essential, because the undercut 11 can be made as a circular slot in the base of the adapter and intercepting the bottom surface of the base (not illustrated). This construction is feasible, because the buttons 8 can be made with contractible and expansible flanges 10 enabling them to be assembled radially into their guiding holes in the base 6, said flanges expanding in the space provided by the undercut or circular slot after such insertion of the buttons.

Preferably the upper part of the adapter, as at the inwardly extending annular portion 7, fits the spindle closely as already stated. In practice, this condition in connection with adapters for bobbins and spools of all kinds may be difficult to obtain and/or maintain (e. g. because of wear), and to prevent looseness at all times, a centering and frictional retaining spring 15 is provided. The spring is U or hairpin-shaped as shown, and of generally flat, i. e. elongated rectangular, cross section. The loop or base 17 of the spring can be secured in a longitudinal groove 16, which passes along opposite sides of the spindle and across its end, by bending in opposite wall portions 18 of the spindle which define the uppermost portion of the groove, so that said wall portions overhang the spring. The groove 16, at all portions of it which receive the spring, is at least deep enough fully to receive the spring with the exposed surface of the latter flush with or not protruding radially materially beyond the adjacent spindle surface. Normally, the spring 15 protrudes from the groove, as at thickened portions 19 of the spring, to enable taking up play between the spindle and adapter or spool or bobbin, and beneath the thickened portions 19 of the spring the groove is correspondingly deepened. When the thickened portions 19 are depressed into the groove a predetermined distance, as against the bottom of the groove, then the outer or exposed surfaces of said spring portions 19 which are appropriately curved make circular continuations of the spindle surface. If desired, for keying the upper part of the spindle to the adapter, the adapter portion 7 can have a pair of grooves (20, Fig. 5) to receive the portions 19 of the spring 15. The upper end of the spindle can be cylindrical to a point below the adapter portion 7, if desired, or slightly conical, and in either case, it is made snugly to fit the portion 7 (e. g.) of the adapter in the operating position of the latter.

Both the yielding connections at the top and base of the adapter can be modified or altered in construction, while nevertheless securing the adapter against rotation and undesirable shifting on the spindle. One modification of the base connection of the adapter (illustrated by Figs. 6 and 7) comprises the provision of a locking-ring 21 which can be sprung into a groove 22 in the adapter base portion, and adapted as by several nose portions to contact resiliently with a similar groove in the rim 4 to secure the adapter against vertical movement on the spindle and holding the base concentric with the spindle. Cooperating herewith to prevent relative rotation of the adapter and spindle, a pair of pins 24, which extend upwardly from the bottom of the cup or the whorl—, loosely occupy respective portions of the cross slot or groove 25 in the base or merely sockets for the pins, larger internally than the pins in cross section.

When the described construction is used, e. g. for a warp yarn bobbin, the bobbin fits over the adapter. When used for the internally smaller weft yarn bobbin, the latter is frictionally held on the bare spindle by the spring shoes 19, and the lower end of the bobbin is limited in its downward movement and is supported as on a shoulder 26 (see Fig. 1). For spinning warp yarn on the same spindle, the adapter 5, which externally can be varied to suit the type of bobbin customarily used, replaces the weft yarn bobbin, and a suitable number of pressure coupling elements 27 on the adapter will enable a considerable variety of tapers, sizes and lengths of warp yarn bobbins to be mounted for operation interchangeably.

The form of adapter shown in Fig. 8 has an upper coupling element which enables locking of the adapter against rotation and/or against turning on the spindle. In other words, it can be used for both purposes or only one of them as may be requisite. As illustrated, a generally cylindrical body 30 is pressed into a bore 31 leading downwardly from the top end. The body has two or more grooves 32 which contain respective coupling levers 33 fulcrumed as at 34 against the bore 31. The levers have lower end nose elements 35 adapted to grip the adjacent portion of the spindle, as at an annular groove 36 thereof (Fig. 8), or at notches or tangential grooves 37 (Figs. 10 and 11). In the latter instance, a positive locking is secured between the adapter and spindle against turning and also lengthwise movement. The upper portion of the body 30 is bored to receive a lever-operating head 39 and releasing button 41 connected thereto; the head being normally pressed upwardly by a spring 40 supported as by a bridge 40a of the body 30. The head 39 is appropriately shaped to cam against the inwardly inclined ends 38 of the levers and to cause the locking of the adapter to the spindle above described, and as will be obvious from the drawings. The release button 41 has an internally beveled rim 42 adapted to bear inwardly against the lever ends 38 upon downward movement of the buttons to release the latching or locking of the lever nose portions 35 on the spindle. The levers can be prevented from falling out of position, i. e. from grooves 32, when the adapter is lifted off the spindle, by extensions 43 of the levers which project downwardly beyond wall portions 30a of the body. Said portions 30a block the inward movement of the extensions 43 and hold the locking nose elements in such position that they can

easily be cammed outwardly by the tip of the spindle when the adapter is applied thereto.

When the coupling just described is used, the locking levers 33 could preclude practical use of the retaining spring 15 in the form heretofore described. In said instance, or in any appropriate ones for that matter, the spring 15', which has its loop extending through a hole 44 near the top end of the spindle and its legs 19' embracing the spindle at grooves 16', can be used. A suitable form of the spring, at the main pressure region (19') of it, is illustrated in Fig. 13. At other portions, the spring can be a flat strip as illustrated in Fig. 14. The curved cross section of the spring along the regions designated 19' stiffens those portions of the spring and enables effective application of spring force to a bobbin on the bare spindle, and enables positive locking (against rotation) of the adapter 5 by the spring 19' (as already described in connection with Fig. 5) when the form of groove 36 exhibited by Figs. 8 and 12 is used at the top of the spindle.

The lower portion of Fig. 8 shows a detachable driving coupling comprising radially disposed pins 46 secured in respective aligned bores in a central or hub portion of the whorl and its rim, which pins drivingly engage downwardly facing notches 45 in the base portion of the adapter. This construction is not required when tangential grooves such as 37 or equivalent keying means is or are used at the upper coupling. Fig. 9 shows the principles of construction of the detachable coupling of Fig. 8 (upper part) embodied in a complex construction for the lower portion of the adapter 5. In this case, a body member 30' is pressed into the lower end of the adapter and is suitably machined to receive the locking levers 33', the lower inwardly extending ends 36' of which engage the whorl hub at radial holes or sockets 47 therein. The actuating and releasing member 41' for the levers, whose operation will be obvious, is pressed upwardly by the spring 40' to move the ends 36' inwardly. Release is accomplished by inserting a suitable tool through side openings in the adapter wall and pressing downwardly on the head 41' which corresponds to the button 41 of Fig. 8. Instead of requiring a downward push on the button 41 or 41', the button may be turned to release the levers through a helical groove or spiral cam formation.

The adapter can overlap the neck or rim of the whorl either inwardly therefrom (as shown) or outwardly.

I claim:

1. A demountable adapter for spinning spindles characterized by having a detachable resilient coupling means arranged for and being operable to secure the adapter against rotation and longitudinal shifting on the spindle.

2. An improvement in a spinning spindle having a whorl provided with an opening, said improvement comprising an adapter with releasable resiliently operated means to engage such opening of the whorl and to latch the adapter in place on the spindle.

3. The improvement according to claim 2, wherein the whorl has an upstanding flange with holes therethrough; and yieldable members on the adapter project outwardly into the holes to effect the latching, which members can be released by pressing them inwardly as described.

4. A demountable adapter for a spinning spindle, which spindle has a transverse external groove or notch in it, spring actuated levers carried by the adapter extending longitudinally of it and each arranged at one end to grip the spindle at such groove or notch, and means on the adapter and cooperable with the levers to swing them to a spindle-releasing position.

5. A demountable adapter and spinning spindle combination, said adapter and spindle having overlapping parts, one part provided with a peripheral groove, a resilient locking ring carried by one of the parts and which engages the groove at regions spaced circumferentially of the whorl in a manner tending to prevent axial separation of the parts, and means connecting the adapter and spindle in a manner to prevent relative rotation.

6. A demountable adapter for a spinning spindle, said adapter having, near one end, a plurality of spring-pressed and releasable levers, each with a portion which enters a groove in the spindle in a manner to prevent relative rotation and also axial movement of the adapter and spindle.

7. A demountable adapter for a spinning spindle, said adapter having a retaining device for engaging the spindle, comprising levers contained within an axial bore of the adapter and held yieldingly in position to engage the spindle by a resilient element bearing on the levers, and cooperating means to hold the levers in such bore when the adapter is removed from the spindle.

8. An adapter according to claim 7, wherein the levers are operated to active position by a head which is in turn acted upon by the resilient element, which head has a portion accessible from a point externally of the adapter to enable release of the spindle by the levers.

9. The combination with a spinning spindle and an adapter therefor, of a hairpin-shaped spring, the legs of which occupy longitudinal grooves in the spindle and normally protrude therefrom by the spring stress, which spring is operable to retain a bobbin on the bare spindle, the adapter having means adapted to interlock with the protruding portions of the spring in a manner to key the adapter to the spindle.

10. A demountable adapter and spinning spindle combination, wherein means for preventing relative rotation is situated at or near one end of the spindle and adapter assembly, and releasable means for preventing relative longitudinal movement is situated at or near the opposite end thereof.

11. A demountable adapter and spinning spindle combination, wherein a whorl portion of the spindle and the adapter base have, respectively, overlapping parts, one carrying a pin and the other a slot cooperable with the pin to lock the adapter against rotation on the spindle.

12. In a spindle such as a spinning or twisting spindle, a U-shaped spring with legs on opposite sides of the spindle lying in longitudinal grooves in the spindle, which legs have outwardly bowed spool or bobbin-engaging portions intermediate of the connecting base and free end portions, characterized in that the base portion of the U occupies a transverse groove in the free end of the spindle, and a side of the groove is deformed inwardly into abutting relation to said base portion to hold the spring against endwise movement.

CARL STAUFERT.
